ORNAMENTAL TOP FOR CIGARETTE TINS

Louis W. Rice, deceased, late of New York, N. Y., by Joseph A. Despres, Scarsdale, N. Y., and Jacques B. Rice and Stanley M. Isaacs, New York, N. Y., executors, assignors to Bernard Rice's Sons Incorporated, a corporation of New York

Refiled for abandoned application Serial No. 640,158, October 29, 1933. This application April 24, 1934, Serial No. 722,138

6 Claims. (Cl. 41—34)

This improvement relates particularly to an ornamental auxiliary metal top that can be readily attached to the lid of the usual tin or carton of 50 cigarettes, while the contents are being removed. Cigarette tins or cartons of 50 are usually gotten up in supposedly artistic style with various decorations and/or printed matter, indicating the brand and qualities of the contents, the lids and boxes being printed and/or lacquered in various colors.

These tins or cartons of 50 cigarettes of the various brands are usually practically the same size and in some cases, may be exactly of the same dimensions, so that the same ornamental top can be used, and an ornamental top is desirable, for the tins or cartons of any brand when displayed on a table or dresser in the home or at a club are not particularly ornamental, although indicating perhaps a favorite brand.

One object of the present improvement, therefore, is to provide an auxiliary ornamental metal top for cigarette tins or cartons or the like that may be readily attached to the lid of ordinary tins or cartons of 50, and will hide or cover over the usual brand name and any other printed matter that ordinarily appears conspicuously on the lid of such a carton or box. The proposed ornamental tops are preferably made of sheet metal, but any suitable material may be used and the design may be stamped, engraved, etched and/or enameled, or otherwise made a permanent feature of the top, the top being such as would be manufactured as a jeweler's novelty and sold independently.

A further object, in the preferred form, is to form the auxiliary ornamental top out of flat sheet metal, the top face of which will carry the desired ornamental design, said plate being preferably provided at its edge with downwardly extending means for attaching the ornamental top to the lid of the cigarette tin or the like. The auxiliary ornamental top is not for permanent attachment to the lid of a tin or carton, such attachment being only temporary, that is, during removal of the contents, so that as soon as the tin or carton is empty, the top may be removed and attached to another filled tin or carton.

The fifties of some of the popular brands of cigarettes are packed and sold in cardboard cartons instead of tin boxes, but the size is substantially the same as with the tins of 50. It is, therefore, contemplated to provide an ornamental auxiliary top of similar design that may be attached to the lid of cardboard cartons or boxes

of 50, or to other types of boxes of the same character.

Any suitable means may be employed for attaching the auxiliary ornamental top to the lid of the cigarette tin, but in the present instance, it is found preferable to form the top plate with downwardly extending resilient flanges and/or members adapted to resiliently engage the side walls of the lid of the tin or carton so as to temporarily cling to the lid but may be readily removed for attachment to the lid of another tin or carton.

Examples of the improved ornamental auxiliary top for cigarette tins or cartons and the like are shown in the accompanying drawing, in which Fig. 1 is a perspective view of one form of ornamental top attached to the cigarette tin of a well known brand; Fig. 2 is an enlarged transverse section of the tin shown in Fig. 1 with one form of auxiliary top attached; Fig. 3 is an enlarged broken away section of part of the lid of a tin with the ornamental top of Fig. 1 partially removed; Fig. 4 is an enlarged section on the line 4—4 of Fig. 3 to illustrate the open corner construction; Fig. 5 is an enlarged broken away view of a modified form of ornamental top shown in connection with a portion of a cigarette tin; Fig. 6 is a similar enlargement of another form and Fig. 7 is a perspective view of a modified form of auxiliary top.

Referring to the drawing, the usual box or tin for holding 50 cigarettes is represented at A. the flanged lid B of which is hinged to the rear wall of the box at C.

In the form of ornamental auxiliary top shown in Figs. 1 to 4, a metal plate D finished in gold, silver or the like, and carrying on its upper face E an ornamental design, is provided with depending flanges F, which are preferably formed integral with the top plate, being bent downwardly therefrom at substantially right angles, as indicated in Figs. 2 and 3.

The downwardly extending flanges F are slightly resilient to closely engage the wall of the lid of a tin and, if preferred, may be curved at the lower ends G to facilitate springing the auxiliary top on to the lid of the tin. In some cases, this may not be necessary, since the corner of the lid B is slightly rounded, as indicated at H. It will be noted that in order that the flanges F may be entirely free for resilient movement, the corners thereof, as indicated at K in Fig. 4, are not united.

This construction makes it possible for the auxiliary ornamental top to be readily attached

to the usual tins of 50 cigarettes, so that the latter when placed on a table in the home or club becomes an ornamental article, rather than an advertisement for a particular brand of 5 cigarettes, and when the tin is empty may be readily detached.

The ornamental auxiliary top may be further ornamented by extending the width and length of the top plate at L, as shown in Fig. 5, and 10 by forming the depending resilient flanges M into a reverse curve giving a molding effect, but still serving as the resilient members for attaching the ornamental top to the walls of the lid of the tin.

15 A slightly different ornamental effect may be obtained by a flat reverse fold N all around the edges of the plate D, as shown in Fig. 6, thereby forming a rounded bead O. In this form the resilient flanges or members P extend downward 20 from the inner edge of the bead so as to engage the lid of the tin, substantially as in the previous forms.

25 Still another form is shown in Fig. 7, wherein depending resilient flanges Q which do not extend the full width or length of the top plate D and are formed as resilient tongues for engaging the side walls of the lid of the tin. This form may be particularly adapted for attachment to the lids of cardboard boxes of 50 cigarettes, since the lids of cardboard boxes are usually attached to the body of the box in a different manner from the attachment of the lid on fifties tins, but the other forms may be modified for fifties in cardboard boxes or the like.

30 35 Obviously, the arrangement is not limited to the forms shown, for other modifications in the means for attaching an ornamental top to the lid of fifties tins, cartons or the like or to similar boxes of other kinds, where such a top is suitable, are available according to the form of the lid and the desired method of attachment.

40 45 The face or top of the ornamental auxiliary top may be of gold or silver or suitably plated, or it may be lacquered or enameled in any color desired and the design on the top may be stamped, etched, printed or engraved thereon alone or in combination with enameled portions, in any suitable or preferred manner known to the novelty jeweler's trade. No claim, however, 50 is here made for any particular design on the top, the design shown as an example being merely selected as illustrative, but it will be understood that, if desired, a design for each particular brand of cigarettes may be employed.

55 While several preferred forms of the improvement have been shown, it will be understood that various modifications may be made in the construction and arrangement of the means for attaching the ornamental top to cigarette tins or the like, and the shape and size of the top itself 60 and the design carried thereby may be varied without departing from the spirit and scope of the invention.

What is claimed is:

1. An ornamental top for temporary attachment to the lid of a carton of cigarettes while the contents are being removed, comprising a sheet metal top plate, an ornamental design on said plate and a plurality of integral resilient members extending from the edges of said plate for resiliently engaging the side walls of the lid of the carton for the temporary attachment of the ornamental top thereto. 5

10 2. An ornamental top for temporary attachment to the lid of a carton of cigarettes while the contents are being removed, comprising a sheet metal plate having thereon an ornamental design, the edges of said plate being reverse 15 folded to form rounded beads, and a plurality of resilient flange members extending from said bead edges for engaging the walls of the lid of the carton, the lower edges of said resilient members flaring outward for the purpose de- 20 scribed. 15

25 3. An ornamental top for temporary attachment to the lid of a carton of cigarettes while the contents are being removed, comprising a metal plate, an ornamental design on said plate, a plurality of independently movable S-curved 30 resilient flanges depending from the edges of said plate, said flanges being free from each other at the corners of the plate and adapted for resiliently engaging the side walls of the lid of the carton for attaching the ornamental top thereto. 30

35 4. An ornamental top for temporary attachment to the lid of a carton of cigarettes while the contents are being removed, comprising a metal plate, an ornamental design on said plate and a plurality of resilient tongue-like members extending from the edges of the plate for resiliently engaging the side walls of the lid of the carton for temporarily attaching the ornamental 40 top to said lid. 40

45 5. An ornamental top for temporary attachment of the lid of a carton of cigarettes while the contents are being removed, comprising an ornamental top member formed of a metal plate and depending individually acting integral means carried by said plate for attaching said ornamental top to the lid of the carton. 55

50 6. An ornamental top for temporary attachment to the lid of a carton of cigarettes while the contents are being removed, comprising an ornamental top member and independently acting integral means depending therefrom for engaging the flange of the lid of the carton for attaching the ornamental top thereto. 55
